UNITED STATES PATENT OFFICE

GEORGE R. ALEXANDER, OF OAKLAND, CALIFORNIA

WATER-SUPPLY SYSTEM

Application filed June 6, 1923. Serial No. 643,604.

The present invention relates to improvements in water supply systems of the type embodying apparatus for pumping water from a source of supply into a tank and 5 causing the delivery of the water from said tank by means of air pressure.

The primary object of the invention is to provide simple and efficacious means for compressing and delivering air into the storage tank and for maintaining the air pressure in said tank within a predetermined 10 working range.

Another object of the invention is to provide means of the character described in 15 which the water forced from the pump into the tank serves as the air compressing medium and the pipes connecting the pump and tank serve as a medium for conducting the air and water to said tank.

20 A further object is to generally simplify and improve the construction, arrangement and mode of operation of water supply system apparatus so as to reduce the cost of installation and upkeep, render the 25 system more certain and reliable in its operation and do away with special air compressing apparatus, such as additional motors and pumps, or means providing for the introduction of air through the pump itself, 30 which latter arrangement causes a loss of efficiency in the pump.

The invention possesses other advantages and features, some of which, with the foregoing, will be set forth at length in the 35 following description wherein I shall outline in full that form of the invention which I have selected for illustration in the drawings accompanying and forming a part of the present specification. In said drawings 40 I have shown one form of the construction but it is to be understood that I do not limit myself to such form since the invention as expressed in the claims may be embodied in a plurality of forms.

45 Referring to the drawings:

Fig. 1 represents a vertical sectional view partly in side elevation of apparatus of the invention.

50 Fig. 2 is an enlarged fragmentary vertical

sectional view of a special valve construction forming a part of the apparatus.

Fig. 3 is a view similar to Fig. 1, of a modified form of the invention.

Fig. 4 is a detail sectional view of the 55 valve employed in the form of the invention shown in Fig. 3.

In carrying out my invention the apparatus employed is of a simple, compact nature and is adapted to be incorporated 60 through pipe connections with a standard water supply system, embodying a hydro-pneumatic pressure tank for storing the water supply, a pump for delivering water from a source of supply, such as a well or 65 cistern, into the tank, and automatically operated means so associated with the tank and pump motor that it will automatically start and stop the motor, depending upon the air pressure or water level within the 70 tank. Heretofore in order to maintain an air pressure within the tank sufficient to insure service, the ordinary air compressing units have been connected directly with reciprocating pumps or those other than 75 centrifugal or rotary, air has been introduced through the pump casing and forced with the water to the tank through the pipe connection. In the former case, employment of an air compressing motor or a standard type 80 of air compressing unit of any character involves an additional expense of installation and upkeep and renders the operation of the system less reliable. In the latter case, the efficiency of the water pump is im-

paired by the introduction of air into the 85 pump itself. In all attempts to reliably and effectively, but within a reasonable cost of installation and upkeep, introduce air and maintain the requisite air pressure, results 90 have been more or less unsatisfactory.

I connect with the piping leading from the pump to the storage tank an air compressing chamber having an inwardly opening check valve arranged to permit air to 95 enter said chamber. This chamber is so arranged that when water is forced by the pump to the storage tank, it may be directed into the air compressing chamber whereby the air in said chamber will be compressed 100

and precede the water through said pipe connections to the said hydro-pneumatic pressure or storage tank.

The invention consists essentially in the provision of means of a nature such as generally described, which causes the water delivered by the pump prior to its being discharged in the storage tank, to compress air and force the air thus compressed into the storage tank, at the same time that the latter is being supplied with water.

Referring particularly to the drawings, wherein I have illustrated one practical embodiment of the invention, 1 designates a 15 foot valve carried upon a pipe 2, extending into a well or other source of water supply, not shown. The pipe 2 is connected with a centrifugal pump 3 mounted upon a base 4 and operated by a motor 5, preferably an 20 electric motor. The pipe 6 extends from the pump 3, and by means of a T coupling 7 is connected with a pipe 8, which latter through a T coupling 9 is connected with and arranged to discharge into the lower 25 side of a hydro-pneumatic pressure or storage tank 10. From the coupling 9, a pipe 11 leads to service pipes or mains, not shown. Mounted upon the tank 10 is an automatically operated device 12 of standard construction, well known in the art, for the purpose of automatically opening and closing the electrical circuit for the motor, depending upon the air pressure in the tank 10. As such controlling devices are well known 35 in the art, it is thought unnecessary to illustrate and describe the same in detail.

The apparatus of my invention comprises an air compressing chamber or tank 13, the lower end of which is connected with the T 40 coupling 7 by pipes 14 and 15, which latter are joined by a Y coupling 16. A coupling 17 is mounted upon the upper end of the tank and extending therefrom are coupled pipes 18 and 19, the latter of which is connected by a coupling 20 with the pipe 8. On one side of the coupling 20 in the pipe 8, there is provided a check valve 22 which opens to permit the discharge of air and water through the pipe 8 and coupling 9 into 45 the tank 10 but prevents water from passing back through the pipe 8 towards the pump. Likewise, the hand valve 21 is provided so that it may be closed to prevent air and water passing from the pipe 19 into the pipe 50 8; from passing back through the pipe 8 into the pipe 6 and pump 3. A similar hand valve 23 is mounted in the pipe 15 between the couplings 7 and 16, whereby the discharge of water from the pipe 6 into the 55 pipes 8 and 15 may be regulated as desired. The Y coupling 16 houses an automatic check valve generally designated 24, which valve comprises a flat shutter or plate 25 hinged or pivoted at one end or edge as at 26, so 60 that it will normally lie in an inclined posi-

tion upon a seat 27 provided at the inner end of one of the terminal portions 28 of the coupling. Preferably the coupling is divided into halves, said halves being threaded together, whereby the assembly of the coupling has a downwardly extending drain pipe 30 connected therewith and the inner end of this branch is adapted to be closed by the valve 25 during the operation of the pump, there being provided a seat 31 at the inner end of the portion 29 against which the valve engages. The remaining terminal portion or extremity 32 of the coupling 16 is connected with the lower end of the pipe 14, which latter leads directly into the chamber 13. A relief port 33 is provided in the valve 25 to permit of the discharge of water through said port, whereby the pressure will be reduced sufficiently to permit the valve to gravitate into position closing the portion 28 so as to prevent flow of water to the pump when the latter ceases to operate, the valve engaging the seat 31 being so inclined that it will, upon removal of the pressure holding it closed, gravitate into its other closing position.

Air to be compressed in the chamber or tank 3 enters the latter through an inwardly opening check valve 34 mounted upon the coupling 17.

Operation

To prepare the apparatus for service, the valve 21 is closed and the valve 23 is opened, air of atmospheric pressure having entered the tank 13 through the check valve 34. When the pump is started the water will be drawn through the pipe 2 into the pump 3 and forced therefrom through the pipe 6 into the pipe 15. The force of the water or impact thereof against the valve 25, which normally lies so as to close the upper end of the terminal portion 28, will cause the valve to move into a position closing the drain or outlet portion 29 and the pressure of the water forced by the pump will maintain said valve in said position so long as the pump is in operation. The water will then pass freely through the coupling 16, pipe 14, and into the tank or compartment 13, causing the air therein to be compressed. The air compressed will precede the water through the coupling 17, pipes 18 and 19, coupling 20, pipe 8, check valve 22 and coupling 9, into the tank 10. When the compressed air delivered to the tank 10 reaches a predetermined pressure, say forty pounds, the automatically operated device 12 will close the circuit for the motor 5 and said motor will cease to operate. By manipulation of the valves 21 and 23, the amount of water to be delivered to the tank in proportion to the requisite amount of air, may be varied as desired and this will be determined by the relative sizes of the apparatus, particularly the tanks 10 and 3 and the setting of the au-

tomatically operated device 12. As soon as the pump stops, the check valve 22 will prevent back flow of water through the pipe 8. When the pump ceases to operate, the pressure of the water in the tank 13 is equal to the pressure within the tank 10 and the valve 25 will be maintained in position closing the outlet member 29 for such period of time as is required for sufficient amount of the water to leak through the port 33 that will cause the pressure of the water in the tank 13 and coupling 16 to be reduced. The valve will gravitate into closing or checking position to prevent back flow of water into the pump. This requires but a short period of time to effect automatically checking or closing of the valve and the water trapped in the apparatus will drain through the member 29 and pipe 30 back to the source of supply. When the pressure in the tank 10, due to leakage or to the withdrawal of the water supply in said tank, is reduced to a point below working factor, say for example thirty pounds, the automatically operated device operates as described to close the circuit for the motor 5 and the pump will immediately begin to operate so that the water and air supply to the tank 10 will be replenished after the manner first described.

In Fig. 3 of the drawings there is shown a slightly modified form of the invention wherein there is connected with a pipe 53 leading from a source of water supply, not shown, a centrifugal pump 54 operated by a motor 34, both pump and motor being supported on a base 35. Leading upwardly from the pump 32 is a pipe 36 which communicates with the lower end of an air compressor chamber 37. Extending from the upper side of the chamber 37 is a pipe connection 38 leading to the lower side of a storage tank 39. A check valve 40 is mounted in the pipe 38 to control the passage of compressed air and water to the tank. Connected by means of a fitting 41 with piping 38 is a suitable inwardly opening check valve 42 arranged to permit air to enter the compressor chamber 37 but to prevent air from passing out of the compressor chamber 37 or piping 38. An automatic valve 43 is connected by a piping 44 to the pipe 36 and extending from the valve 43 is a discharge pipe 45. The automatic valve 43 comprises a globular casing 46 having nipples 47 and 48 to which the pipe lines 45 and 44 are connected. At the inner end of the nipple 47 is a valve seat 49 against which a ball valve 50 seats under certain operating conditions. The ball normally rests upon protuberances 51 clear of the inner end of the piping 44 so as to not interfere with the discharge of water from said pipe into the valve casing.

The operation of this form of the invention is substantially the same as in the other

form, the only difference being that by pass piping leading from the pump directly to the tank is done away with, the only passage to the tank being through the compressor chamber. As the water is pumped through the pipe 36, part of it passes through the piping 44 into the valve and the impact of the water against the valve causes the same to move upwardly against the seat 49 and to shut off communication with the discharge pipe 45. The pressure of the water being pumped maintains this valve closed. The water passes upwardly into the compressor tank, compresses the air therein and the compressed air preceding the water enters said tank through the piping 38. By means of an electrical controlling device generally designated 52, associated with the tank 39, as in the preferred form of the invention, when the air pressure within the tank reaches a predetermined point, the electrical controlling device shuts off the motor 34 and the pump ceases to operate. As soon as the pump ceases, the pressure of water on the ball valve is reduced and the valve drops into normal position shown in Fig. 4. The water draining from the tank 37 will then pass through the pipe 44, valve casing 43 and out through the discharge pipe 45. The force of the water returning or passing through the pipe 44 is not sufficient to lift the valve 51 to its seat 49. The water will pass beneath the valve between the protuberances 51 so that the full force thereof is not directed upon the valve and therefore in this way the valve does not interfere with water draining from the system. The suction produced by the water draining from the compressor tank induces a quantity of air through the check valve 40 into the compressor chamber 37 so that upon the next operation, air will be compressed and delivered to the main tank. The main tank is obviously connected with a water distribution system, not shown. The valve 40 closes as soon as the motor ceases to operate.

This form of the invention is more simple, compact and permits of the use of standard fittings in this construction.

I claim:

1. A water supply system embodying a tank, a rotary pump for delivering water from a source of supply into said tank, an air compressing chamber, means for causing water forced by said pump to enter and compress air in said chamber and means for conducting compressed air from said chamber into said tank.

2. A water supply system embodying a tank, a rotary pump for delivering water to the tank, an air compressing chamber, means for causing water forced by said pump to enter and compress air in said chamber and means for conducting com-

pressed air and water from said chamber into said tank.

3. A water system embodying a storage tank, a rotary pump for delivering water to said tank, an air compressing chamber, means causing water forced by said pump to enter and compress air in said chamber, means operating to stop the pumping operation when the pressure of air in the tank reaches a predetermined point, a drain pipe connected with the means of communication between the pump and compressor chamber, an automatic valve acting to shut off communication with the drain pipe upon operation of the pump and to communicate the drain pipe with said means of communication when the pump ceases to operate.

4. A water system embodying a storage tank, a rotary pump for delivering water to said tank, an air compressing chamber, means causing water forced by said pump to enter and compress air in said chamber, means operating to stop the pumping operation when the pressure of air in the tank reaches a predetermined point, a drain pipe connected with the means of communication between the pump and compressor chamber, an automatic valve acting to shut off communication with the drain pipe upon operation of the pump and to communicate the drain pipe with said means of communication when the pump ceases to operate and an inwardly opening check valve through which air is introduced into the compressing chamber upon drainage of water from said chamber.

5. A water supply system embodying a storage tank, a rotary pump for delivering water from a source of supply into said tank, means for conducting water from the pump to the tank, an air compressing chamber, a pipe connection between said conducting means and said compressing chamber and a pipe connection between the compressing chamber and storage tank.

6. A water supply system embodying a storage tank, a rotary pump for delivering water from a source of supply into said tank, means for conducting water from the pump to the tank, an air compressing chamber, a pipe connection between said conducting means and said compressing chamber and a pipe connection from the air compressor tank to said conducting means.

55. 7. A water supply system embodying a storage tank, a rotary pump for delivering water from a source of supply into said tank, means for conducting water from the pump to the tank, an air compressing chamber, a pipe connection between said conducting means and said compressing chamber, a pipe connection from the air compressor tank to said conducting means and valves 60 for independently controlling the introduc-

tion of water to said compressor chamber and storage tank respectively.

8. A water supply system embodying a storage tank, a rotary pump for delivering water from a source of supply into said tank, means for conducting water from the pump to the tank, an air compressing chamber, a pipe connection between said conducting means and said compressing chamber, a pipe connection from the air compressor tank to said conducting means, valves for independently controlling the introduction of water to said compressor chamber and storage tank respectively and means automatically draining off the water having entered said compressor tank, when the pump ceases to operate.

9. A water supply system embodying a storage tank, a rotary pump for delivering water to said tank, an air compressing chamber, means for causing water which has passed through said pump to enter and compress air in said chamber and means for conducting air from the chamber to said tank.

10. In a device of the character described, the combination of a pressure tank, rotary means for forcing liquid into said tank, and trap means for delivering a quantity of gas into said tank at each period of operation of said means for forcing said liquid into said tank, and automatically functioning to recharge the trap with a fresh charge of gas during each inoperative period of said liquid forcing means.

GEORGE R. ALEXANDER.
